UNITED STATES PATENT OFFICE.

VLADA MILLITY, OF DETROIT, MICHIGAN.

NONREFILLABLE BOTTLE.

1,408,376.

Specification of Letters Patent. Patented Feb. 28, 1922.

Application filed October 25, 1920. Serial No. 419,455.

To all whom it may concern:

Be it known that I, VLADA MILLITY, a citizen of Jugo-Slavia, residing at Detroit, in the county of Wayne and State of Michigan, have invented certain new and useful Improvements in Nonrefillable Bottles, of which the following is a specification, reference being had therein to the accompanying drawings.

10 My invention aims to provide a novel closure member for receptacles, and more particularly bottles containing medicine or beverages. It is a well known fact that bottles which once contained a popular brand 15 of beverage or a particular kind of medicine are often refilled with an inferior beverage or medicine, and to eliminate this nefarious practice I have devised a closure member which at all times closes a bottle, 20 but provision is made for opening the closure member and also for rendering the closure member inoperative, whereby an empty bottle may be positively closed against surreptitious filling. By such a closure member 25 it will be impossible to use bottles for other purposes which once contained poison matter.

My invention further aims to provide a bottle closure which may be built into a bottle neck and obviate the necessity of providing a cork or separate closure.

My invention still further aims to accomplish the above results by a construction that will be hereinafter described and then 35 claimed, and reference will now be had to the drawing, wherein—

40 Figure 1 is a vertical sectional view of a portion of a bottle neck, showing the closure member in side elevation and partly in section with the member in a closed position;

Fig. 2 is a vertical transverse sectional view of the bottle neck showing the closure member partly in elevation and an open position;

Fig. 3 is a plan of the bottle neck, partly in horizontal section and showing a portion of the closure member in plan;

Fig. 4 is a side elevation of the bottle neck, 50 partly in section on the line IV—IV of Fig. 2, and

Fig. 5 is a perspective view of a detached stationary ring member which provides a knife or severing device.

55 In the drawing, the reference numeral 1

denotes a bottle neck which is preferably molded or made in halves suitably connected together, and the bottle neck has a globular or oblate spheroidal shaped head 2 provided with a discharge opening 3 having for 60 its axis the bottle neck 1.

Diametrically opposed inner walls of the head 2 are provided with recesses 4 and 5, the latter being comparatively large with a tangentially disposed opening 6 communicating therewith.

In the head 2 is an oscillatory closure member 7 provided with an opening 8 adapted to establish communication between the discharge opening 3 and the bottle neck 1, 70 and the opening 8 is adapted to have its ends closed by opposed walls of the head 2, as shown in Fig. 1. Opposite walls of the closure member 7 are provided with trunnion or pivot members 9 and 10 disposed axially of the recesses 4 and 5 and loosely engaging in the inner walls of said recesses so as to support the closure member 7 for an oscillatory movement within the head 3. Encircling the trunnion or pivot member 9 is a 75 coiled spring 11, having one end thereof anchored relative to the closure member 7 and the opposite end thereof anchored in the wall of the recess 4 so that the retractile force of the spring may retain the closure member 7 in a closed position with the axis of the opening 8 at a right angle to the axis of the opening 3 and the bottle neck 1. 80

Projecting from the wall of the recess 5, adjacent its outer edges, are positioning lugs 90 12 and fitting over these lugs and held against rotation is a peripheral flange 13 of a ring member 14, the flange thereof being notched, as at 15 to receive the lugs 12. The ring member is best shown in Fig. 5 and is 95 provided with openings 16, 17 and 18, with the opening 17 communicating with a slot 19 having its walls tapering inwardly so as to provide a knife or severing instrumentality 20, the purpose of which will practically appear.

That wall of the closure member 7, opposite the trunnion or pivot member 9, is formed with a cylindrical boss or integral pulley 21, having a peripheral groove and a 105 transverse opening 22. Suitably anchored in the opening 24, for instance as at 23, is a flexible member 22 which has its ends extending out of the opening 24, and with the boss or pulley 21 journaled in the stationary 110

ring member 14, there is sufficient clearance between the boss and the ring member for the passage of the flexible member about the boss through openings of the ring member 14. Referring to Fig. 1, one end of the flexible member extends under the boss 21 and outwardly through the opening 16 of the ring member 14 and through the opening 6. This end of the flexible member is designated 10 25 and may be conveniently termed the short end of the flexible member.

The opposite end of the flexible member 22 extends over the boss 21 through the opening 18 of the ring member 14 on to the 15 periphery of said ring member. The flexible member then enters the slot 19 or the opening 17 to bear on the boss 21, and then the end of the flexible member extends through the opening 16 and passes through the opening 6 to provide a long end designated 26. The manner in which the flexible member is trained about the boss 21 permits of either 20 end of the flexible member being pulled upon to partially rotate the closure member 7, and to 25 limit the movement of the closure member it has a stop pin 27, best shown in Fig. 3, which extends into a segment shaped recess 28 communicating with the recess 5, and it is the end walls of the recess 28 which afford 30 abutments for the stop 27, so that the closure member 7 can be turned fully a quarter of a revolution either to open or close said member.

At the juncture of the head 2 with the bottle neck 1 there is an internal flange 29 affording a seat for a gasket, washer or packing ring 30 which is made of compressible material and the gasket is adapted to be compressed when the closure member 7 is turned to a closed position, as shown in Fig. 1. This may be accomplished in two ways. First, the wall of the closure member 7 may be slightly enlarged so as to have the action of a cam when the closure member is turned, 45 and second, the trunnions or pivot members 9 and 10 may be placed slightly off center so that the closure member 7, when turning, will have somewhat of an eccentric action within the head 2 and thus cause the gasket 50 to be compressed and seal the connection between the bottle neck and the closure member, when said closure member is in a closed position.

Considering the operation or utility of the closure member, I will assume that the manufacturer of the bottle delivers the same to a beverage manufacturer with the closure member 7 in a closed position which is held by the retractile force of the spring 11. In order that the beverage manufacturer may fill the bottles, the short end 25 of the flexible member is pulled upon and the closure member 7 turned a quarter of a revolution, which places the opening 8 of the closure

member in registration with the opening 3 65 of the head 2. In so turning the closure member the spring 11 is placed under additional tension so that upon the short end 25 of the flexible member 22 being released the spring will restore the closure member to a 70 closed position. However, the short end of the flexible member is held while the bottle is filled and then the short end 25 is cut off close to the opening 6, so that when the closure member 7 automatically turns to a 75 closed position the short end of the flexible member is drawn into the head 2 and cannot again be manipulated. This still leaves the long end 26 of the flexible member protruding from the opening 6 and in such condition 80 the bottle is handed to the consumer of the contents of the bottle.

To obtain the contents of the bottle the long end 26 of the flexible member is pulled upon and the closure member 7 again placed 85 in an open position. With the flexible member 22 in the form of a cord, string or some material capable of being severed it is now possible for the flexible member to be severed by the knife 20 when the long end 26 90 of the flexible member is released. Before releasing the long end of the flexible member the bottle is empty and then when the long end 26 is released the turning closure member 7 pulls upon the flexible member and in 95 so doing drags said member in the slot 19 and into the narrow or knife end thereof. Bearing in mind that the member 14 is stationary and the boss 21 movable therein, it is obvious that the flexible member wedging 100 in the slot 19 will be cut by the knife 20. The long end 26 of the flexible member will be released and may be pulled from the opening 6, and it is now impossible to manipulate the closure member 7 and open the bottle. 105

One embodiment of this invention has been illustrated, but it is to be understood that the structural elements are susceptible to such variations and modifications as fall within the scope of the appended claims. 110

What I claim is:—

1. The combination of a bottle neck, a rotary closure member therein, retractile means maintaining said closure member normally closed, a flexible member attached to said closure member and adapted to be pulled upon to open said closure member and then cut off, another flexible member attached to said closure member and adapted to be pulled upon to open said closure member, and means carried by said bottle neck adapted to automatically cut the last mentioned flexible member when the closure member assumes a normally closed position. 115

2. The combination set forth in claim 1, 120 wherein said bottle neck has a globular head with said closure member trunnioned therein. 125

3. The combination of a bottle neck, a ro-

tary closure member therein, retractile means maintaining said closure member normally closed, a flexible member attached to said closure member and adapted to be pulled down upon to open said closure member, and means within said bottle neck adapted to sever said flexible member when said closure

member assumes a normally closed position.

In testimony whereof I affix my signature in presence of two witnesses.

VLADA MILLITY.
